VENTILATED RESISTOR

Charles C. Whittaker, Pittsburgh, Pa., assignor
to Westinghouse Electric & Manufacturing
Company, East Pittsburgh, Pa., a corporation
of Pennsylvania

Application April 11, 1941, Serial No. 388,058

13 Claims. (Cl. 201—74)

My invention relates, generally, to resistors and it has reference, in particular to ventilated resistors.

Generally stated, it is an object of my invention to provide a compact ventilated resistor that is simple and inexpensive to manufacture and is highly efficient in operation.

More specifically, it is an object of my invention to provide for directing a cooling medium against a resistor having resistance elements of the edge-wound type and utilizing interior core members and exterior baffle members to form cooling ducts between adjacent turns of the elements for the cooling medium so as to secure the maximum cooling with a minimum of cooling medium.

A further object of my invention is to provide for more rapidly dissipating heat from a resistance element of the edge-wound type so as to permit a relatively small resistance element to handle safely large amounts of power.

Another object of the invention is to utilize internal core members and external baffle members with resistance elements of the edge-wound type to provide a plurality of ducts between the adjacent turns of the elements which present relatively low resistance to the flow of a cooling medium.

Another object of my invention is to provide for supporting a resistance element of the edge-wound type by baffle members on each side of the element which function to direct the flow of a cooling medium between adjacent turns of the element.

Still another object of my invention is to provide for supporting a plurality of edge-wound resistance elements in spaced relation by means of baffle members positioned between the elements to substantially fill the space therebetween and direct a cooling medium between the adjacent turns of the elements.

A further object of my invention is to provide for mechanically interlocking a plurality of resistance elements and baffle members which are positioned between the resistance elements to direct a cooling medium into intimate contact with the elements.

Other objects will in part be obvious, and will in part be explained hereinafter.

My invention provides a highly efficient ventilated resistor for application where the amount of power to be handled is large and the space available is small without the danger of excessive heating. In practicing the invention in a preferred form, the resistance elements may each comprise a plurality of turns of a ribbon of suit-

able resistance material wound on edge in a generally helical shape. Refractory core members are positioned within the element and provided with spaced ribs or projections for supporting the turns in spaced relation, and baffle members of a refractory material are positioned between the adjacent elements to substantially fill the space therebetween. The baffle members are provided with enlarged end portions on the front and back sides of the elements to interlock mechanically therewith, and opposed surface portions conforming generally to the shape of the adjacent portions of the elements so as to define, with the core members a plurality of ducts between the turns of the elements. The resistor is mounted in a casing and a cooling medium directed against one side of the elements by means of a suitable blower to force the cooling medium through the ducts formed between the adjacent turns of the elements between the core and baffle members.

For a more complete understanding of the nature and scope of my invention, reference may be had to the following detailed description which may be taken in connection with the accompanying drawings, in which:

Figure 1 is a front elevational view partly in section of a ventilated resistor unit embodying the principal features of the invention;

Fig. 2 is a side elevational view partly in section of the resistor unit shown in Fig. 1;

Fig. 3 is an enlarged plan view of the resistor shown in the resistor unit of Fig. 1;

Fig. 4 is an enlarged vertical sectional view along the line IV—IV of Fig. 3;

Fig. 5 is a front elevational view of a modified form of resistor embodying the principles of the invention;

Fig. 6 is a sectional view taken along the line VI—VI of Fig. 5;

Fig. 7 is an enlarged partial view in section taken along the line VII—VII of Fig. 5;

Fig. 8 is an enlarged partial view in section taken along line VIII—VIII of Fig. 5; and

Fig. 9 is an enlarged partial view in section taken along the line IX—IX of Fig. 6.

Referring to Figs. 1 and 2, the reference numeral 10 may denote, generally, a ventilated resistor unit comprising a resistor 12, which may be positioned within an enclosure 13 and provided with ventilating means such as the blower 14 for directing a cooling medium such as air therethrough.

The enclosure 13 may be of any suitable construction, comprising, for example, a frame struc-

ture 15 having partitions 16 with openings 17 therein, positioned intermediate the top and bottom to divide the enclosure into sections. The upper section may be enclosed at the sides by means of suitable side panel members 18, and provided with an opening 19 at the top. The resistor 12 may be supported in the upper section in any suitable manner, such as by means of bracket members 20 secured to the frame structure.

The blower 14 may be positioned between the partitions 16 and the openings 17 therein utilized as inlets and outlets therefor. The blower 14 may be driven by a motor 21, which may be mounted in the lower section of the enclosure and connected to the blower by a belt 22. The central and lower sections of the enclosure 13 may be provided with perforated side panel members to substantially enclose the motor and blower, and provide for the ingress of air to the resistor. A suitable terminal board 24 may be mounted adjacent the resistor for making connections thereto.

Referring to Figs. 1, 2, 3 and 4, it will be seen that the resistor 12 may comprise a plurality of elongated resistance elements 25, supported between end frame members 26 of insulating material by means of tie rods 27, which may be connected to the bracket members 20. Side frame members 28 may be secured between the end frame members 26 by means of angles 29 to substantially enclose the elements on all sides.

The resistance elements 25 may comprise spaced turns 30 of a ribbon of suitable resistance material wound edgewise and generally helical in form. While the elements are shown as having circular sections, it will be understood that they may have other sections, such as oval or flattened circular sections without departing from the scope of the invention. Core members 32 of refractory material having serrated surfaces may be positioned within the elements to maintain the turns in spaced relation. The core members may be mounted on the elongated support bars 34, which may be provided with slots 35 on the inner surfaces to receive the bars. The ends of the bars may be provided with slots 36, as shown in Fig. 2, to receive the tie rods 27 and support the bars thereon. Tubular spacers 38 may be positioned on the tie rods 27 between the support bars 34 to maintain the elements in spaced relation.

In order to provide for cooling the resistor elements 30 in a most efficient manner, suitable means, such as the baffle members 40 may be positioned between the adjacent elements to substantially fill the spaces therebetween and force the cooling medium to pass directly between the adjacent turns of the elements. The baffle members 40 may be made of any suitable refractory material capable of withstanding relatively high temperatures, and may be positioned between the adjacent elements in any suitable manner. For example, opposite sides 41 of the baffle members 40 may be dished transverse to the longitudinal axis of the element, as shown, conforming, generally, to the curved edge portions of the elements 25. The baffle members will, therefore, have substantially dumbbell shaped sections which are narrower in the mid portion and wider adjacent the ends. When the baffle members are positioned between the adjacent elements, the enlarged end portions 42 mechanically interlock with the elements and prevent movement of the baffle members transverse to the longitudinal axis

of the elements, thus securely positioning them therebetween. If desired, the baffle members 40 may be provided with projecting ribs 43 along the front and back edges of the dished surface portions so that direct contact with the resistance elements may be made by means of the projecting rib portions, thus making it easier to align the baffle members with the resistance elements, since the area of contact therebetween is thus greatly diminished and variations of dimensions in manufacturing are rendered less material.

Referring to Figs. 5 through 9 of the drawings, the reference numeral 45 designates, generally, a modified form of resistor wherein a plurality of resistance elements 46 comprising spaced turns 47 of a ribbon of resistance material wound on edge may be supported between the end frame members 48 by means of a plurality of refractory baffle members 50, secured to the end frame members by means of tie rods 51.

As shown in Fig. 7, the resistance elements 46 may be supported on elongated metallic support bars 52 by means of refractory core members 53 positioned on the opposite edges of the support bars. The core members 53 may be provided with serrated surfaces so as to form projecting finger portions 54 at spaced intervals which may be positioned between the turns of the resistance element to retain them in spaced relation.

The end frame members 48, which may be of a suitable insulating material such as, for example, asbestos board, may be provided with a plurality of transverse slots 55 having recessed portions 56 adjacent the central portion of the end frame for receiving the ends of the support bars 52. Suitable openings 57 may be provided in the end frames in alignment with the slots 55 to receive terminals 58, which may be provided with an enlarged head portion 59 having a projecting rib 60 adapted to be positioned in the slot 55 to prevent the terminal from turning. The resistance elements 46 may be connected to the terminals 58 in any suitable manner, such as, for example, by means of the welds 60.

In order to provide for directing a cooling medium between the adjacent turns of the resistance elements 46, and for also supporting the elements, the baffle members 50 may be provided with surface portions 62 on the opposite sides thereof conforming, generally, to the curvature of the outer edges of the resistance elements and rounded end portions 63 on the front and back having substantially greater width than the mid-portion of the baffle member, as shown in Fig. 9. Suitable longitudinal openings 66 may be provided through the enlarged end portions of the baffle members to receive the tie rods 51 and tubular spacing members 66, which enable the nuts 67 on the tie rods to be drawn tight without applying excessive pressure to the baffle members themselves.

Since the baffle members 50 which are positioned between the adjacent resistance elements 46 have a substantially dumbbell shaped section, 65 pockets are, in effect, provided between the adjacent baffle members for receiving the resistance elements. Because of the enlarged end portions of the baffle members, the resistance elements are securely locked in position between the adjacent baffle members, which not only provide for directing a smooth and uniform flow of cooling medium between the ducts, thus formed between the adjacent turns of the resistance elements and the baffle and core members, but also assist in positioning and supporting the resistance elements.

Since the elements are effectively supported throughout their length by the baffle members 50, the elements may be made much longer than usual, without any danger of sagging. The resistor of Figs. 5 through 9 is shown as having a single row of resistor elements. Such a resistor may be used in applications where only a relatively low pressure is available for forcing the cooling medium therethrough. Where greater pressures are available and greater capacity is needed, such units may be arranged in tandem as desired.

From the above description and the accompanying drawings, it will be apparent that I have provided a simple and efficient ventilated resistor wherein the baffle members, which are interlocked with the resistance elements, may be supported by or may themselves support the resistance elements. A smooth, non-turbulent flow of a cooling medium may thus be confined to the immediate space between the adjacent turns of the resistance elements so that efficient cooling of the elements may be secured and relatively large amounts of power may be handled with a relatively small resistor requiring only a relatively low pressure to force the cooling medium through the cooling ducts.

By utilizing with resistors of the edge-wound type baffle members of the type I have hereinbefore described, whereby the resistance element and baffle member are mechanically interlocked, much greater heat dissipation may be secured from a given length of resistance than was heretofore possible. With the arrangement shown in Figs. 5 through 9, the resistance elements may be safely operated at much higher temperatures than heretofore without fear of sagging. In addition, longer elements may be used, since the baffle members interlock therewith and support the elements, since the path of the air or other cooling medium is limited by the baffle and core members to substantially the spaces between the turns of the elements. For a given volume of air, more than ten times the usual heat dissipation secured by merely blowing air between the elements may be obtained by utilizing the arrangement embodying my invention.

Since different embodiments of the invention may be made, and changes made in the drawings and above description without departing from the spirit thereof, it is intended that all matter contained in the above description or shown in the accompanying drawings shall be considered as illustrative, and not in a limiting sense.

I claim as my invention:

1. A resistor comprising an elongated core member of insulating material, a resistance element including a plurality of spaced turns of an edgewise wound ribbon of resistance material of generally helical form positioned about the core member, and a pair of elongated baffle members of insulating material so positioned on opposite sides of the element and having transversely curved surface portions in juxtaposition to the outer edges of the turns of the resistance material so shaped as to define with the core member a plurality of relatively long arcuate channels between adjacent turns of the element throughout substantially the full length of the element.

2. An elongated resistance element comprising, an edgewound ribbon of resistance material formed generally into a helix, a core member positioned within the element, and an elongated baffle member positioned on each side of the re-

sistance element having a longitudinal groove conforming generally to the outer portion of the turns to receive the said outer portion and define with the core member and the turns of the helix a plurality of ducts from one side of the element to the other of substantially the width of the ribbon, said baffle members being arranged to partially surround the element and interlock mechanically therewith to prevent relative movement of the element and baffle member in a direction transverse to the longitudinal axis of the element.

3. A resistor comprising, a generally helical resistance element having a plurality of spaced turns of resistance ribbon wound on edge, a refractory core member positioned within the element, and a pair of elongated baffle members positioned on opposite sides of the element having transverse curved surface portions positioned in engagement with the outer edges of the turns thereof cooperative with the core member and the turns of the resistance ribbon to define a plurality of relatively long open ducts confined between the adjacent turns for a cooling medium throughout substantially the length of the element.

4. The combination with a resistor having an elongated resistance element comprising a plurality of edgewise wound turns of ribbon of resistance material positioned in spaced relation on a core member, of a pair of elongated refractory baffle members having surface portions conforming generally to the contour of the outer edges of the turns of the element transversely and contiguous therewith throughout substantially the length of the element positioned on opposite sides of the element to partially enclose the element and define with the core member a plurality of arcuate ducts between the adjacent turns from one side of the element to the other.

5. A resistor comprising, a frame, an edge-wound resistance element having spaced turns of resistance ribbon of generally helical shape, a refractory core member positioned within the element having a plurality of spaced teeth between the turns of the element, and refractory members supported in the frame having surface portions conforming generally to and engaging the outer edge portions of the element throughout substantially the length of the element positioned in opposed relation on opposite sides of the element to secure the resistance element therebetween and to define a plurality of ducts between and bounded by the turns of the element for a cooling medium.

6. The combination in a resistor, of a plurality of elongated resistance elements comprising spaced turns of a ribbon resistance material wound on edge, a core member positioned within each element and connected to a supporting frame, and baffle members positioned in substantially continuous end to end relation between adjacent elements having curved surface portions conforming substantially to the adjacent portions of the element shaped to define with the core member a plurality of arcuate ducts of substantially the width of the ribbon from one side of the element to the other and enlarged end portions on opposite sides of the elements projecting inwardly to partially enclose the elements and interlock mechanically in a transverse direction with the said elements to provide a substantially continuous baffle throughout the length of the elements and to retain the baffle members in end to end relation between the elements.

7. The combination with a resistor having a plurality of elongated edgewound resistance elements with a plurality of turns of ribbon resistance material wound on edge and positioned on core members supported in a frame, of a plurality of baffle members having generally dumbbell shaped sections with opposed surfaces conforming generally to the outer edges of the turns of adjacent elements to define with the core member relatively long arcuate ducts of substantially the width of the ribbon from one side of each element to the other and enlarged portions on opposite sides of the elements positioned between adjacent elements to interlock mechanically therewith and secure the baffle members between the elements.

8. A resistor comprising, a plurality of elongated resistance elements having a plurality of spaced edgewound turns of ribbon resistance material, a plurality of core members having spaced finger portions positioned within the elements to maintain the turns thereof in spaced relation, a frame structure, and a plurality of baffle members extending substantially continuously throughout the length of the elements positioned between the elements and supported by the frame structure having recesses on opposite sides to receive and partially enclose the outer edges of the turns, whereby said baffle members support the elements between adjacent baffle members against movement transverse to the longitudinal axis of the elements and define a plurality of ducts between the turns thereof.

9. A resistor comprising, a plurality of resistance elements comprising generally helical edgewise formed spaced turns of a ribbon resistance material, a frame, means including refractory core members positioned within the elements to support them in spaced relation in the frame, and a plurality of refractory baffle members positioned in juxtaposition between adjacent elements having opposing surface portions substantially contiguous with the outer edges of the turns of the adjacent elements shaped to define with the core member arcuate ducts between adjacent turns for a cooling medium and enlarged end portions on each side of the elements having a width greater than the space between adjacent elements to interlock mechanically with the elements and secure the baffle members relative to the frame.

10. A resistor comprising, a plurality of elongated resistance elements positioned in spaced relation with openings therebetween and having edgewise formed spaced turns of a ribbon of resistance material, a core member positioned within each element having spaced projections on the outer edge positioned between the turns to maintain them in spaced relation, a frame having spaced end members, a plurality of refractory support members positioned in the openings between adjacent elements having surface portions adjacent the elements throughout the length of the elements conforming generally to the outer

edge portions of the elements to provide substantially enclosed ducts between the turns thereof in a direction substantially transverse to the longitudinal axes of the elements for a cooling medium and restricted portions between adjacent elements with enlarged end portions on the front and back sides of the openings between the elements partially surrounding the elements so as to interlock mechanically with the elements and position them in the frame, and means connecting the end members operative to secure the support members in the frame.

11. A resistor comprising, a plurality of spaced apart resistance elements of a ribbon resistance material wound on edge in a generally helical shape with spaced turns, a core member positioned within each element having projecting portions to retain the turns thereof in spaced relation, a plurality of baffle members having generally dumbbell shaped sections positioned between adjacent elements to interlock mechanically therewith and provide ducts between the adjacent turns of the elements for a cooling medium, end frame members, rigid connecting means securing the end frame members in spaced relation effective to secure the baffle members to the end frame members, and terminal members connected to the resistance elements mounted on the end frame members.

12. A resistor comprising, an elongated edgewound ribbon resistance element of generally helical form, a plurality of refractory core members positioned within the element having surface recesses to receive the turns to maintain them in spaced relation and an elongated metal support positioned within the refractory core members, a terminal secured to an end of the element having a headed stem with a projecting rib on the stem side of the head, an end frame member having a transverse slot to receive an end of the elongated metal support and the projecting rib of the terminal, a pair of refractory baffle members positioned on opposite sides of the element having surface portions adjacent the element conforming generally to the outer edges of the turns of the element and enlarged front and back end portions interlocking mechanically with the element, and means to secure the baffle members to the end frame member with the element therebetween.

13. A resistor for use with means for producing forced ventilation comprising an elongated resistance element having a plurality of spaced edgewise wound turns of a ribbon resistance material positioned on a core member and supported in a frame, of a baffle member extending along each side of the element throughout the length thereof having a longitudinal groove to receive the outer portions of the element shaped to define relatively long and narrow ducts bounded by the turns of the ribbon and interlock mechanically therewith in a transverse direction.

CHARLES C. WHITTAKER.
